JACOB M. SMILER, NATHAN SEGAL, JACOB CHAITT, AND NATHAN RUDIN, OF
PHILADELPHIA, PENNSYLVANIA.

PHONOGRAPH-RECORD ALBUM.

1,398,746.

Specification of Letters Patent. Patented Nov. 29, 1921.

Application filed November 4, 1920. Serial No. 421,652.

To all whom it may concern:

Be it known that we, JACOB M. SMILER, a citizen of the United States, and NATHAN SEGAL, JACOB CHAITT, and NATHAN RUDIN, 5 citizens of Russia, all residing in the city of Philadelphia, State of Pennsylvania, have jointly invented certain new and useful Improvements in Phonograph-Record Albums, of which the following is a full, clear, and 10 exact description, reference being had to the accompanying drawings, forming a part of this specification.

Our invention relates to albums designed to contain talking machine records, and has 15 for its objects to construct such an album so that it will lie flat when opened, and, as an incident to such construction will provide space between the adjacent leaves to compensate for the thickness of the record which 20 is placed in the pocket of each leaf, that will provide a leaf hinge for each leaf independent of the binding; that will guide the records to the sight opening in the leaf pocket and retain each one out of contact 25 with the bending edge of the leaf; that will exclude dust from the binding elements, and that will provide a binding method consistent therewith and fully efficient; these results being affected by a combination of 30 elements which includes, primarily, constructing the leaf pockets in pairs, united at their binding edges and constituting a two leaf signature, preferably making them from a single blank suitably folded, creasing 35 the folded pair on a line parallel with and adjacent to the fold, mounting the signatures in spaced relation on an initial or primary binding, fixedly uniting the latter to a rigid cover back, and so constructing and 40 uniting the binding elements that the signatures may be secured directly through the fold between them to the initial binding and the latter to the cover back, constructed as hereinafter described and both of them, then 45 united, being mounted within the usual casing of the album by glued textile strips interposed between the primary binding strip and the casing.

The construction involves another feature 50 whereby the union of the binding elements is reinforced and protected and whereby dust and air are kept from entering between the binding elements which, otherwise, would tend to loosen the glued parts, and 55 incidentally thereto the rounded form of

the back of the casing is maintained; and finally each pocket leaf is provided interiorly with means, preferably folded strip of like material glued to each leaf at a point forwardly of the creased hinge line of the leaf 60 which is adjacent to and parallel with the fold, and having the double function of not only guiding the record to its proper place within the pocket of the leaf but preventing the edge of the record from extending back 65 to the binding edge between each signature of leaves and hence relieving strain on the binding edge.

In the accompanying drawings illustrating our invention,

Fig. 1 is a perspective view of the album in open position.

Fig. 2 is a plan view of a signature or pair of leaf pockets.

Fig. 3 is a section on line 3—3 of Fig. 2. 75

Fig. 4 is a section at a similar point of a modified means of uniting the pockets of a two leaf signature to prevent the record from striking the binding edge.

Fig. 5 is a plan of the modification shown 80 in Fig. 4.

Fig. 6 is a section on line 6—6 of Fig. 1, enlarged.

Fig. 7 is a section on line 7—7 of Fig. 6.

Fig. 8 is a partial end view of the album 85 edge—shown in Fig. 7.

Fig. 9 is a perspective of one end of the primary backing.

Fig. 10 is a perspective of one end of the rigid backing and

Fig. 11 is a perspective of the covering plate for the ends of the binding elements.

Referring now to said drawings, the numeral 2 indicates a pocket leaf of the album, made from thick flexible paper or 95 the like, as usual, from a blank which is folded on itself to form a pocket having at least one closed edge, two other coinciding edges of the folded parts of the pocket leaf being glued or otherwise secured to each 100 other, while the edges of the folded parts which form the top edge 3 of the leaf are left open to form an opening or entrance to the pocket, and the center of each or both sides of the pocket leaf is apertured, 105 as at 4, for the usual sight openings to display the name or title of the record placed in the pocket.

All such construction is as usual in the art, but in our construction, which is essen- 110

tial to our method of binding them in the book, we make the pocket leaves in two-leaf signatures, which may be effected by the obvious and usual method of uniting the 5 binding edges of two leaves by a strip of suitable textile material glued to and between the coinciding edges of such a pair of pocket leaves. In our construction these two leaf signatures are preferably made 10 from a single blank, as shown in Fig. 2, so that when it is folded over a second time, on a medial line 5 to form a signature of two such leaves such folding line will unite the pair of leaves integrally at that point and 15 form a permanent binding edge 6 whereby to attach the signatures to the primary binding element hereinafter described, but the same effect with respect to the combination with the binding elements may, as is obvious, be effected by a pair of single and 20 separate pocket leaves united as common in the art by the connecting strip above referred to; however, it is apparent that such a usual connecting strip may be employed 25 merely as a reinforcing strip over such a fold or medial line when the pair of pocket leaves are made from a single blank and integrally united to form a common binding edge 6 as in the preferred method first described.

30 Each leaf pocket is creased as indicated at 7 on a line adjacent to and parallel with the medial fold line and binding edge 6, to form a leaf hinge, independent for each 35 leaf, and additional to the more or less rigid binding hinge hereinafter described, and to which the signatures are bound in spaced relation to each other to compensate for the thickness of the records placed in the pockets; the result being that the leaves of the 40 album, when opened, will lie perfectly flat on each other and on the covers of the back, due largely to the independent leaf hinge, formed by the creased line 7, which, as is 45 apparent, will largely relieve the strain on the binding edge 6 relatively to the rigid backing of the book.

We have found it decidedly advantageous to provide a single means within the 50 leaf pocket to effect a triple function, one to guide the record to its proper place with its identifying label opposite the sight opening 4, another to interiorly connect the opposite sides of the leaf pocket substantially on a 55 line central or forward of the independent leaf hinge or creasing, which tends to compel the use of that creased line as the primary if not the sole hinge, and finally to keep the record edge forward from and out of contact with the binding edge. These three 60 functions are performed by a narrow strip of material, such as the paper of which the leaf is formed, indicated at 8, Fig. 2, which is folded and lies interiorly of the pocket leaf from the line of the hinge crease of the 65

leaf toward the sight opening, and is glued to both interior sides of the leaf pocket at the point or part mentioned, and is constructed, as shown in section in Fig. 3, wherein 5 is the binding edge of the two 70 leaf signature, 7 in each leaf is the creased leaf hinge, and 8 is the insert strip above described. Obviously, from the latter view, the insert 8 will prevent the record from passing beyond the leaf hinge crease 7 and 75 keep it away from the binding edge 5, at the same time centering it opposite the sight opening 4 in the leaf pocket. The same function and effects can be produced by a modification, if desired, shown in Figs. 4 80 and 5, wherein an opening 8^a is cut on three lines in one side of the pocket leaf to form a lip 8^b which is then passed through a slit 8^c in the opposite side of the pocket leaf, and glued to the exterior face of the latter. 85 These parts are formed in the leaf members at such point or points that when brought together the leaf members are fastened together at a point immediately adjacent the creased leaf hinge as in the preferred construction first above described.

The leaf signatures being formed as stated, they are rigidly and directly attached, through the uniting fold between them, which forms the binding edge 6, by 95 means such as thread or wire stitching indicated at 9 in Fig. 6, to a primary binding 10 consisting of a strip of semi-flexible but tough material, such as card board, which is provided with creased ends 10^a, intended 100 to overlap the ends of the secondary binding element, which is a rigid backing block, preferably of hard wood, flat on the inner side, and slightly curved on the outer side, as at 11^a, Fig. 10. In order to operatively 105 connect the bound signatures to the usual cover or casing of the book, a thin textile strip, indicated at 13, Figs. 1 and 7 is interposed between the binding edge 6 of the signatures and the primary binding 10, said 110 strip being wide enough on each side to extend beyond the binding elements and be glued to the interior of the casing or cover 115 as usual.

To assemble the parts, the signatures being mounted on the primary backing as stated, the latter is glued to the inner or flat side of the rigid backing block 11, and its creased ends 10^a, which extend beyond the length of said block, are then bent over the 120 ends of the block and fastened thereto in any convenient way. To reinforce the union of said elements, to impart a neat and finished appearance thereto, but primarily to prevent the entrance of dirt and moisture to 125 the binding elements, we provide a metallic plate, shown at 12 in Fig. 11, the back of which is curved to conform to the curvature 11^a of the binding block and has end flanges 12^a resting against the opposite narrow 130

edges of the block 12 and over the overlapping ends 10^a of the primary binding strip fastened thereto. The plate 12 is preferably given an edge incline as indicated at 12^b and a lip extension as at 12^c, to more fully cover the binding elements, thereby giving the bound book the appearance shown in end elevation in Fig. 8. In operation the leaf pockets, when filled with records, indicated at 16, will present the filled appearance shown in Fig. 7, wherein the records are held centered therein and compelling the hinge movement of the leaves to take place largely on the creased leaf hinge 15 rather than on the binding edge of the signatures.

We claim:

1. In a talking machine record album, the combination with a plurality of two-leaf 20 signatures composed of a pair of record-holding leaf pockets united to form a binding edge between them, each leaf being creased to form an independent hinge therefor on a line adjacent to and parallel with 25 said binding edge, a semi-flexible strip to which said signatures are directly and fixedly bound, said strip having overlapping ends, a rigid backing to which said strip is operatively united by its overlapping ends, 30 and means secured over the coinciding ends of said strip and rigid backing operating to reinforce the union of said last named elements and exclude dust and foreign matter from the binding elements.

35 2. In a talking machine record album, the combination with a plurality of two-leaf signatures composed of a pair of record-holding leaf pockets united to form a binding edge between them, each leaf being creased to form an independent hinge therefor on a line adjacent to and parallel with 40 said binding edge, a semi-flexible strip to which said signatures are directly and fixedly bound, said strip having overlapping 45 ends, a rigid binding block exteriorly curved in cross-section to which said strip is glued and additionally united by its overlapping ends, a transversely disposed metallic plate having flanges resting against the opposite 50 longitudinal edges of said binding block and against the interposed overlapping ends of said strip and fixedly secured to said block.

55 3. In a talking machine record album, the combination of a plurality of two-leaf signatures each composed of a pair of record holding leaf pockets united at their coinciding rear edges to form a binding edge between them, each leaf being creased on a line parallel with and adjacent to said binding edge 60 and forming an independent leaf hinge, a primary binding for said signatures consisting of a flexible strip having overlapping ends, said signatures being separately and rigidly attached directly through the binding edge to said primary binding strip and

in spaced relation to each other, a rigid backing block to which said primary binding is operatively united by means of said overlapping ends, and a reinforcing and covering plate provided with flanges overlapping the coinciding ends of said strip and binding block and secured thereto by said flanges. 70

4. In a talking machine record album, the combination of a plurality of two-leaf signatures each composed of a pair of record-holding leaf pockets united to form a binding edge between them, each leaf being creased to form an independent hinge therefor on a line adjacent to and parallel with 75 said binding edge, a semi-flexible strip to 80 which said signatures are directly and fixedly bound, said strip having overlapping ends, a rigid binding block exteriorly curved in cross-section to which said strip is glued and additionally united by its overlapping 85 ends, a transversely disposed metallic plate having securing flanges adapted to engage the overlapping ends of said strip and the binding block and fixedly secured to the latter, said plate being curved lengthwise to 90 conform to the curvature of the back of said binding block and having a lip extension 12^c and an inclined edge 12^b, said flanged plate operating to exclude dust and foreign matter 95 from the binding elements. 95

5. In a talking machine record album, the combination of a plurality of pairs of leaves constructed to operate as record holding pockets, said leaves constructed from a single blank folded on a medial line between them 100 to form a two-leaf signature, each leaf pocket being creased on a line adjacent to and parallel with said fold, a rigid backing, means to secure said signatures in spaced and fixed relation to said rigid backing, and 105 means constituting a part of one member of the pocket leaf glued to the opposite member thereof, said means operating to retain the records forwardly away from the creased hinge of the leaf pocket and from the binding edge between the leaves of each signature. 110

6. In a talking machine record album, the combination of a plurality of pairs of leaves constructed to operate as record holding 115 pockets, each of said pairs of leaves being constructed from a single blank folded on itself longitudinally to form leaf pockets formed by two thicknesses of paper united at the coinciding base edges, and then folded 120 on a medial line between the pockets to form a two-leaf signature, each leaf pocket being creased on a line adjacent to and parallel with said fold to operate as a supplemental hinge for the leaf, means to unite the adjacent interior surfaces of each pocket member in the region immediately adjacent to but forward of said creased line and operating to hold a record in the pocket from passing sidewise therein, a rigid binding block, 125 130

and means to secure each of said signatures at its rearward binding edge in spaced relation to each other and in direct and fixed relation to said rigid binding block.

- 5 7. In a talking machine record album, the combination with the casing cover and a rigid back binding, of a plurality of two-leaf signatures mounted in spaced relation to each other and independently secured directly and rigidly on said rigid back binding, each of said signatures consisting of a pair of leaf pockets united at the rear edge to form a binding edge, and creased on a line parallel with and adjacent to said line to 10 form an independent hinge for each leaf, a strip glued to and between the interior faces 15 of each of said leaves, said strip extending

only to said creased line, whereby the medial line of union between the leaves is reinforced and whereby also the records are guided to 20 a position in the pockets opposite the sight opening therein and forwardly away from said binding edge of each signature.

In testimony whereof, we have hereunto affixed our signatures this 28th day of October 25 A. D. 1920.
